Robert W. Hardie

UNITED STATES PATENT OFFICE.

ROBERT W. HARDIE, OF YONKERS, NEW YORK.

SCARF-PIN GUARD.

1,015,265.

Specification of Letters Patent. Patented Jan. 16, 1912.

Application filed September 8, 1911. Serial No. 648,372.

To all whom it may concern:

Be it known that I, ROBERT W. HARDIE, a citizen of the United States, and a resident of the city of Yonkers, in the county of Westchester and State of New York, have invented certain new and useful Improvements in Scarf-Pin Guards, of which the following is a full, clear, and exact description.

My invention relates to means for securely holding a scarf pin in a scarf of the wearer, so as to prevent the pin from working loose, or from being removed from the scarf without the wearer's knowledge.

Other objects connected with the construction and mode of operation of the several parts constituting my invention are herein-after set forth.

These objects I accomplish by the means hereinafter described, and illustrated in the accompanying drawings, wherein I have shown my invention in the form preferred by me, and wherein similar characters of reference indicate corresponding parts throughout the several views.

In the drawings, Figure 1, is a side elevation of a scarf pin guard embodying my invention. Fig. 2 is a vertical transverse section taken on the axial line of Fig. 1.

As illustrated in the drawings, 1 represents the main body of the guard, preferably cylindrical in outline, and provided with an insertion aperture 2. The end of the body opposite the insertion opening is provided with an inclined wall 3, flaring outwardly, and that end of the body is also provided with an exterior shoulder 4. A head 5, having an inclined wall 6, is arranged within the recess formed by the wall 3 of the body, and is provided with a central aperture 7 in line with the aperture 2 of the body of the guard, to receive a scarf pin. The head 5 is also provided with apertures 8 extending laterally through said head and adapted to receive balls or gripping devices 9, to grip and hold a scarf pin. A coiled spring 10 bears against the shoulder 4 of the body, and preferably encircles the body of the guard. The head 5 is provided with a sleeve 11 which may be formed integral with the head, or it may be formed separately from said head and connected therewith by turning the edge of the sleeve over the lateral edge of the head 5, so as to form a shoulder 12 on said sleeve. The opposite edge 13 of said sleeve is turned inward so as to overlap and inclose the spring 10. By

means of said construction the movements of the sleeve 11, control the movements of the head 5.

When the guard is in use, the point of the scarf pin 14 is inserted within the opening 2, while the body of the guard is held by the user, and when the pin is pressed downward it comes in contact with the balls 9, of the head 5, which are of a size sufficient to project somewhat into the aperture 7 of the head 5, when not in use on a scarf pin. The inward pressure of the pin against the balls 9 forces the head outward slightly from the body, and permits the balls 9 to move laterally in the aperture 8, and the pin is then pressed through the head 5 until it projects the desired distance through the central aperture 7 of said head. When the inward pressure on the pin is removed, the spring 10 bearing against the shoulder 4 of the body and against the inner edge 13 of the sleeve 11 presses inward the sleeve 11 and the head 5 connected therewith. The inward movement of the head 5 causes the balls 9 to come in contact with the inclined wall 3 of the body of the guard, and forces said balls inward so as to grip the scarf pin held within the central aperture 7 of said head. If an effort be made to remove the scarf pin surreptitiously from the scarf of the wearer, the pull on the pin tends to draw the head 5 farther inward into the more contracted portion of the recess formed by the inclined wall 3 of the body of the guard, thereby increasing the pressure of the balls 9 on the scarf pin, and preventing the pin from being withdrawn from the guard. And as the guard is arranged on the pin at the back of the scarf, the pin cannot be withdrawn from the guard. When it is desired by the user to remove the guard from the pin, the sleeve 11 is drawn outward from the body 1 by the user, thereby bringing the gripping balls 11 into a wider portion of the recess in the end of the body formed by the inclined wall 3, and when the head is in such position, the balls 8 are free to move laterally in their bearings, and the scarf pin may be readily removed from the guard.

Having thus described my invention, what I claim as new and desire to secure by Letters Patent, is:

1. A scarf pin guard, comprising a body having an insertion opening, and provided at the end of the body opposite the insertion end with an inclined wall flaring outwardly

and with a shoulder extending outwardly from said body, a head having a central aperture to receive a scarf pin and with lateral apertures, friction balls arranged with-
5 in said lateral apertures and adapted to extend into the central aperture of said head and to bear against said inclined wall of said body, a coiled spring encircling said body and bearing against said shoulder, and a
10 sleeve overlapping and inclosing said spring and provided with a shoulder connected with said head.

2. A scarf pin guard, comprising a body having an insertion aperture at one end, and
15 at the opposite end an interior inclined wall

flaring outwardly, a head provided with a sleeve inclosing the adjacent end of said body, and with a gripping device adapted to bear against said inclined wall, and means arranged between said sleeve and body adapt- 20 ed to press said head toward said inclined wall by spring tension.

In testimony whereof I have hereunto set my signature in the presence of two attesting witnesses.

ROBERT W. HARDIE.
